UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

DROP DOOR FOR RAILWAY CARS

Original application filed April 26, 1929, Serial No. 358,305. Divided and this application filed January 19, 1931. Serial No. 509,716.

My invention relates to the construction of railway cars of the dumping or drop bottom type such as hopper cars, hopper gondola cars, drop bottom or general service gondola cars or the like, having a door forming a part of the car for retaining the load therein, which door is provided with hinges adjacent one of its edges and is capable of being "dropped" or swung open to discharge the load. Any means of raising the door to the closed position and any means for locking and releasing the door may be employed with my device. Such a door is commonly called a "hopper door". My doors may also be used 10 as drop end gates or doors for mill type gondola cars.

The object of the invention is to provide a door for a railway car with a substantially circular rib or reinforcement forming a drum head whereby a load upon the door normal to its load sustaining surface draws the metal toward the center of the circular rib which is resisted by the arcuate construction of the rib and to connect the circular ribs of adjacent doors in a car by a spreader, which 20 spreader preferably is secured to two parts of each circular rib.

In the drawings:

Fig. 1 shows part of a railway car incorporating my invention.

Fig. 2 is a section on line 2—2 of Fig. 1 showing the door and associated parts and also the spreader.

Fig. 3 is a plan view of one of the doors 30 showing a circular rib and the spreader.

Fig. 4 shows a modified construction.

The drawings show my improved door applied to a hopper car wherein the entire car, or at least the major portion thereof, consists of a hopper with the lower portion thereof divided into a plurality of small hoppers or chutes, which chutes are provided with doors 9 swingably supported to a part of the car by hinges 10. Any convenient means 40 may be used to close and lock the doors.

The form illustrated comprises a shaft 11 extending between opposite sides of the car which is mounted upon the center sills 12 and provided with an eccentric arm 13 connected to the spreader 14 by a connecting rod 15.

My improved door comprises a substantially rectangular body portion which is provided with a circular or substantially circular rib 21 forming a drum head wherein any vertical load imposed upon the door within the circular rib tends to draw the rib inwardly; in other words, to flatten the circle, which tendency is resisted by the arcuate construction of the ribs, as the force is resisted by a part of the circular rib which could be described as an arch. The spreader 14 is secured to the door so as to transmit the raising force to the circular rib and preferably to two parts of each circular rib of each door.

By the term "circular" I mean anything substantially so; for instance, the hexagonal construction shown in Fig. 4.

I have shown and described the circular rib and several means of reinforcing the circular rib to better enable it to perform its function. However, any one or all of the several means may be used and still come within the scope of this invention.

The accompanying drawings illustrate the 75 preferred form of the invention, though it is to be understood that the invention is not limited to the exact details of construction shown and described, as it is obvious that various modifications thereof, within the scope of the 80 claims, will occur to persons skilled in the art.

This is a division of my co-pending application Serial No. 358,305, filed April 26, 1929.

I claim:

1. In a railway car, the combination of a pair of doors hinged to the car for simultaneous operation, each of said doors comprising a body with a circular reinforcing rib there-

- for, a spreader, and a door raising mechanism associated with the spreader, said spreader secured to the door so as to transmit the raising force to the circular rib.
- 5 2. In a railway car, the combination of a pair of doors hinged to the car for simultaneous operation, each of said doors comprising a body with a circular reinforcing rib therefor, a spreader, and a door raising mechanism associated with the spreader, said spreader secured to the door so as to transmit the raising force to two parts of the circular rib.

GARTH G. GILPIN.
